UNITED STATES PATENT OFFICE.

ANDREW HOWARD, OF PITTSBURG, PENNSYLVANIA.

DESIGN FOR AN ELECTRIC-LIGHT SHADE.

SPECIFICATION forming part of Design No. 19,329, dated October 1, 1889.

Application filed August 13, 1889. Serial No. 320,642. Term of patent 3½ years.

To all whom it may concern:

Be it known that I, ANDREW HOWARD, a citizen of the United States, residing at Pittsburgh, in the county of Allegheny and State of Pennsylvania, have invented certain new and useful Improvements in Design for Gas-Globes; and I do hereby declare the following to be a full, clear, and exact description of the invention, reference being had to the accompanying drawing, which forms part of this specification.

This design for an electric-light or gas shade consists of a bowl having its lower half or body of cylindrical or nearly cylindrical form, rounded off toward the neck, while the upper half is flared and crimped, as shown in the drawing, the flare having an abrupt inclination outward of the shell from the upper part of the cylindrical bowl.

Any suitable surface decoration is imparted 20 to the shade.

I claim--

The design for an electric-light or gas shade, consisting of the cylindrical bowl or body having rounded base and a flaring crimped 25 mouth, the flare or inclination proceeding abruptly from the body and of approximately the same depth as the cylindrical portion, as shown.

In testimony that I claim the foregoing I 30 have hereunto set my hand this 12th day of July, 1889.

ANDW. HOWARD.
